(57) **CLAIM**

We claim the ornamental design for a motor with encoder, as shown and described.

DESCRIPTION

FIG. 1 is a front side elevation view of a motor with encoder embodying our design;

FIG. 2 is a rear side elevation view of the motor with encoder shown in FIG. 1;

FIG. 3 is a right side elevation view of the motor with encoder shown in FIG. 1;

FIG. 4 is a left side elevation view of the motor with encoder shown in FIG. 1;

FIG. 5 is a top plan view of the motor with encoder shown in FIG. 1;

FIG. 6 is a bottom plan view of the motor with encoder shown in FIG. 1; and,

FIG. 7 is a perspective view of the motor with encoder shown in FIG. 1.

The broken lines shown represent unclaimed subject matter and form no part of the claim. Where broken lines abut a claimed surface it is understood that those broken lines represent an unclaimed boundary between claimed and unclaimed surfaces. None of the broken lines form any part of the claimed design.
